UNITED STATES PATENT OFFICE.

ARTHUR J. KEISER, OF ROCHESTER, NEW YORK, ASSIGNOR TO THE BIRCHER CO., INC., OF ROCHESTER, NEW YORK, A CORPORATION OF NEW YORK.

ENVELOPE-SEALING MACHINE.

Application filed January 2, 1920. Serial No. 348,944.

To all whom it may concern:

Be it known that I, ARTHUR J. KEISER, of Rochester, in the county of Monroe and State of New York, have invented certain 5 new and useful Improvements in Envelope-Sealing Machines; and I do hereby declare the following to be a full, clear, and exact description of the same, reference being had to the accompanying drawings, forming a 10 part of this specification, and to the reference numerals marked thereon.

My present invention relates to envelope sealing machines of the nature set forth in my pending application Serial No. 233,890, 15 filed May 11, 1918, which has resulted in Patent No. 1,426,745, dated August 22, 1922, and it has for its object to improve upon that machine in several particulars including the feeding mechanism and the matter of properly manipulating the envelope so that it 20 will be properly presented to the moistening device. The present improvements are directed in part toward rendering the machine more capable of handling bulky envelopes and toward so constructing the moistening devices that the gummed flap will be drawn over properly against the body of the envelope so that the crease will be taut and flat and the flap will not wrinkle or bulge. 25 To these and other ends the invention resides in certain improvements and combinations of parts all as will be hereinafter more fully described, the novel features being pointed out in the claims at the end of the 30 specification.

In the drawings:

Figure 1 is a side view of an envelope sealing machine constructed in accordance with and illustrating one embodiment of my invention;

Figure 2 is a top view thereof;

Figure 3 is a side view corresponding to Figure 1 but with the guide plate and parts exterior thereof removed;

Figure 4 is a bottom view;

Figure 5 is a longitudinal section looking toward the side of the machine presented to view in Figure 1;

Figure 6 is a transverse section taken substantially on the line 6-6 of Figure 4, and

Figure 7 is an enlarged fragmentary top view of the moistening devices with parts broken away and an envelope in process of being moistened.

Similar reference numerals throughout the several views indicate the same parts.

To first briefly describe the general character of the machine, envelopes are fed from off the bottom of a stack placed on a table and pass into a runway where they are picked up by the frictional contact of conveyors that carry them successively into the path of a moistening disc that runs between the flap and the body of the envelope, the latter being in a horizontal plane. From the moistening disc the envelope travels on the conveyors through sealing rolls that press the wet gum of the flap against the envelope and complete the operation.

In the present instance, the table 1 (Figure 3) is constituted by the inclined bottom of a hopper 2 having a front retaining partition 3 and 4 indicates the stack of envelopes to be fed. The bottom envelope of the stack at a rearward point rests upon the periphery of a feed wheel 5 extending through and slightly above the table and supported in bearing brackets 6 beneath the latter. The periphery of this wheel is smooth and does not move the envelope except for a contact member 7 preferably constituted of a soft rubber plug having frictional engagement sufficient to move the envelope. Upon each rotation of the wheel 5 this contact member comes up through the table and gives the bottom envelope a forward kick whereupon its front edge is gripped by a carrier belt 7^a also preferably of soft rubber. The said belt runs in the direction of the arrows over a pulley 8 and a grooved roll 9 turning on shafts 10 and 11 supported in side plates 12 and 13 of the main frame 14 of the machine. Associated with the pulley 8 is a small pulley 14^a carrying a spring belt 15 that turns the feed wheel 5 through the medium of a pulley 16 on the shaft thereof.

Just forwardly of the partition plate 3 of the hopper is a grooved presser foot 17 riding on the carrier belt 7^a. This presser foot has a spring pressed stem 18 (Figure 5) supported in a guide member 19 secured to a bracket arm 20 extending from the frame plate 13 which rises to a height permitting it to serve as a guide for the flap edge of the envelope as it travels on the carrier belt 7^a and the continuation thereof hereinafter mentioned. The rear edge of the presser foot is curved upwardly, as shown, and as the bottom envelope is fed forwardly its front or end edge is forced by the presser foot against the belt 7^a and taken up by the latter which draws it beneath the yielding

presser foot and next presents it to an ironing element 21 in the present form of a lateral extension on the rear end of the presser foot. This ironing element smooths 5 and flattens the envelope if it has been bulged or distended by its contents. In other words, it compresses a thick, well filled envelope.

The envelopes are stacked so that their 10 flaps are uppermost and so that the fold of the flap joining it to the body portion runs along the guide plate or finger 23. The bracket arm 20 is provided with an inclined flanged portion 22 that slopes down 15 toward the fold of the flap and if the latter happens to be raised too high or is at right angles to the body of the envelope, this flange in conjunction with a guide bracket 22^a secured to side plate 13 folds it 20 down during its passage being arranged just above or slightly beyond the ironing element 21. Should the flap on the other hand, happen to be folded close against the body of the envelope, it is raised and held spaced 25 therefrom sufficiently to ride over the moistener hereinafter described by a finger 23 having a reverse inclination to the folding flange 22 and also inclined rearwardly, as shown in Figures 2 and 3. This finger is 30 pivoted at 24 to the presser foot 17 and is pressed down in a yielding manner by a spring 25 on the pivot. The point of the finger rides on the periphery of the roll 9 to catch beneath the narrow end of the flap as the end of the envelope passes from 35 the end of a rigid runway 26 formed by an extension of the hopper 2 and table 1. The carrier belt 7^a runs through a slot 27 in this runway and table.

40 The envelope is next seized by a conveyor consisting of a plurality of rubber carrier belts 28 running over the grooved roll 9 and over a similar grooved pulley 29 similarly supported. While on this carrier the gummed 45 edge of the under surface of the flap is moistened by a moistening disc 30 inclined slightly with respect to the plane of movement of the envelope. It is carried on the lower end of a tilted shaft 31 depending from a bracket 50 32 in which it has a bearing and which bracket is supported by the frame plates 12 and 13 to span the runway of the machine, as shown in Figure 2. A transverse shaft 33 also journaled in the bracket 32 55 drives the shaft 31 through the medium of beveled gears 34 and 35 on the two shafts, respectively.

The disc 30 travels in the direction of the carrier 28 but at greater peripheral speed. 60 Its upper surface is roughened or suitably treated to adapt it to carry and spread a film of water which is fed to it from a reservoir 36 through a port not shown by means of a piston 36' connected with a pitman 36" 65 operated by a crank 37' on the roll carry-

ing shaft 49 in a manner set forth in application Serial No. 348,045. As before stated, the disc engages beneath the flap of the envelope and its moist upper surface softens the gum and makes it adhesive and 70 to insure the contact of the gummed edge with such surface, I provide a flap holder 37 that rides on top of the flap and holds it against the disc by gravity pressure. This holder, in the present instance, consists of a 75 curved or bent plate pivoted at 38 to the guide plate 13 of the frame.

By properly choosing the point in the progress of the envelope at which this holder 80 37 causes the most intimate contact between the disc and the gum of the flap, I cause the disc to not only moisten the latter but to draw it over on the body of the envelope and pull the folded edge flat due to the tendency 85 of the gum to adhere to the disc itself. For this purpose, such contact is made beyond the median line of the disc, or at a point where the surface thereof is travelling laterally from beneath the flap as indicated 90 at X in Figure 3.

From beneath the holder 37 the envelope next passes on the carrier 28 between roll 29 and an upper roll 39 that cause the flap to adhere to the body of the envelope and from thence it passes finally between two smoothed pressing rolls 40 that give it the final squeeze and complete the operation. The rolls 39 and 40 are supported by and have bearings in the side plates 12 and 13 except that the roll 29 100 and the lower roll 40 turn on their shafts 41 and 42, respectively, and these are floating shafts carried on the arm of a spring 43 coiled about a stud 44 on the plates 12 and 13 so that the rolls may yield for envelopes 105 of different thicknesses. The plates are slotted at 45 to permit this movement of the shafts. A bridge piece 46 supported on the plate 13 at 47 and by an extension 48 of the bearing bracket 32 carries the bearings 110 for the shafts 49 and 50 of the roll 39 and the upper roll 40.

The machine illustrated is a hand machine and is driven by a crank 51 on the shaft of the carrier roll 9. From a sprocket 52 115 on this shaft a chain 53 runs over a sprocket 54 on a shaft 55 located between the roll 39 and the upper roll 40 and these rolls are positively driven by a gear 56 on the shaft 55 meshing with gears 57 on the roll shafts 49 and 50. An idler roller 58 on an arm 59 pivoted to the plate 13 at 60 and operated by a spring 61 holds the chain 53 in mesh with a sprocket 62 on the shaft 33 through which means the moistening disc is 120 driven. The carriers 7^a and 28 are, of course, driven directly by the shaft 11 of the roll 9 carrying the crank 51.

I claim as my invention:

1. In an envelope sealing machine, the 130

combination with a table for a stack of envelopes, a sealing device, and a continuously travelling carrier delivering to the latter, of a rotary feeder associated with the table 5 to lie beneath a stack of envelopes thereon and operating in timed relation to the sealing device and a contact member on the periphery of the feeder adapted to intermittently frictionally engage the lowermost envelope 10 and urge it toward the carrier.

2. In an envelope sealing machine, the combination with a table for a stack of envelopes, a sealing device, a continuously travelling carrier delivering to the latter, a 15 presser foot cooperating with the carrier and a guide plate arranged between the presser foot and a portion of the carrier that lies beneath a stack of envelopes on the table, of a rotary feed associated with the 20 latter to lie beneath the stack and operating in timed relation to the sealing device and a contact member on the periphery of the feeder adapted to intermittently frictionally engage the lowermost envelope and urge it 25 toward the carrier.

3. In an envelope sealing machine the combination with automatic means for feeding an envelope in a given plane, of a disk mounted to revolve in a plane inclined relatively to said feeding plane and adapted to 30 cooperate with the flap of an envelope to moisten the same while the envelope is being moved by the feeding means; and a flap holder mounted to yieldingly engage the 35 surface of the disk or flap of an envelope thereon at a point adjacent the periphery of the disk where it emerges from between the flap and envelope body.

4. In an envelope sealing machine, the 40 combination with a support for a stack of envelopes, means for feeding the envelopes one by one from said stack in a given plane, of a revoluble moistening element extending 45 into the path of the envelope and adapted to run between the body and flap thereof while the envelope is being moved by the feeding means, and a flap holder arranged to engage the disk or the flap of an envelope thereon at or adjacent to the point where the 50 moving flap passes off the moistening element in its path of movement and the surface of the moistening element moves transversely thereto.

5. In an envelope sealing machine, the combination with a support for a stack of envelopes, means for feeding the envelopes one by one from said stack in a given plane, of a revoluble moistening disk extending 55 into the path of the envelope and adapted to operate between the body and flap thereof while the envelope is being moved by the feeding means, and a flap holder arranged to engage the disk or the flap of an envelope thereon at or adjacent to the point where the flap passes off the edge of the 60 disk and the surface of the disk moves away from the flap.

6. In an envelope sealing machine, the combination with a runway and means for carrying an envelope along the same, of a 70 moistening element adapted to run between the body and flap of an envelope on the carrier and an ironing device arranged above the bottom of the runway in advance of the moistening element to iron out the 75 contents of the envelope.

7. In an envelope sealing machine, the combination with a runway and means for carrying an envelope along the same, of a 80 moistening element adapted to run between the body and flap of an envelope on the carrier and an ironing device for the body of the envelope, a flap holding element and a flap lifting finger arranged in the runway in advance of the moistening element in the 85 order named.

8. In an envelope sealing machine, the combination with a runway and means for carrying an envelope along the same, of a 90 moistening element adapted to run between the body and flap of an envelope on the carrier and a flap folding element and a flap lifting finger arranged in the runway in advance of the moistening element in the order named.

9. In an envelope sealing machine, the combination with a runway and means for carrying an envelope along the same comprising a friction belt and a roll over which it runs, of a moistening element adapted to 100 run between the body and flap of an envelope on the carrier and a yielding inclined flap lifting finger arranged tangentially of the roll in advance of the moistening element.

ARTHUR J. KEISER.
